(57) **CLAIM**

The ornamental design for footwear, as shown and described.

DESCRIPTION

FIG. 1 is a top, rear perspective view of a footwear showing my new design;

FIG. 2 is a bottom, front perspective view thereof;

FIG. 3 is a left side view thereof;

FIG. 4 is a right side view thereof;

FIG. 5 is a rear elevation view thereof;

FIG. 6 is a front elevation view thereof;

FIG. 7 is a top plan view thereof; and,

FIG. 8 is a bottom plan view thereof, and is shown in a lighter contrast than the claimed design in preceding views, indicating that the bottom in its entirety forms no part of the claimed design.

The dot-dash lines illustrate the boundaries of the claimed design and form no part thereof. The lighter contrast portions of the figures outside of the dot-dash lines in FIGS. 1 through 6 and within the dot-dash line in FIG. 7 illustrate portions of the footwear that form no part of the claimed design.
